UNITED STATES PATENT OFFICE.

GUSTAF IVAR BARCLAY, OF DETROIT, MICHIGAN, ASSIGNOR TO DETROIT STEEL PRODUCTS COMPANY, OF DETROIT, MICHIGAN, A CORPORATION OF MICHIGAN.

GLAZING CLIP.

Application filed March 21, 1927. Serial No. 177,144.

The invention relates to glazing clips and has for one of its objects the provision of a clip which may be economically manufactured and permit of its ready assembly with the sash to retain the glass in the sash. Another object is to so form the clip that when in its inoperative position it will permit of the ready assembly of the glass with the sash. A further object is to so form the clip that it and another like clip may be secured to opposite sides of a sash bar by a securing means common to both. With these as well as other objects in view, the invention resides in the novel features of construction and combinations and arrangements of parts as more fully hereinafter set forth.

In the drawings:

Figure 1 is a perspective view of a portion of a window embodying my invention;

Figures 2 and 3 are respectively a plan view and a side elevation of a portion of Figure 1;

Figure 4 is a sectional elevation showing one clip in operative position and another clip in inoperative position.

I have shown the glazing clip embodying my invention as applied to a metal sash 1 having the bar 2 extending between the upper bar 3 and a lower bar intermediate the ends of these bars. The bar 2, as shown, is T-shaped, while the upper bar 3 and the lower bar, as well as the side bars of the sash, are angle shaped, all of these bars having glass supporting flanges 4 extending in substantially the same plane and transverse flanges 5. 6 and 7 are glass panes inserted into the sash and preferably resting upon putty beds 8 which in turn are upon the supporting flanges 4.

For securing the glass panes in place, I provide a number of glazing clips which are secured to the flanges 5 of the sash bars. These glazing clips are alike and but one for each glass pane is shown. This clip is preferably formed of sheet metal, preferably having non-corrosive and resilient properties, such as spring bronze. The clip has the body portion 9 and the transverse flange portion 10. The body portion is adapted to extend substantially parallel to a bar flange 5 and is pivotally connected at one end to this bar flange. The transverse flange portion is formed near the free end of the body

portion and is laterally offset and preferably curved in a direction parallel to the body portion so that with the clip in operative position this transverse flange portion will take care of variations in thickness of either the glass pane or the putty bed or both to properly engage the glass pane, at which time the edge of the body portion opposite the transverse flange portion will extend between the edge of the glass pane and the adjacent bar flange and serve to act as a spacer. The transverse flange portion in addition to holding the glass pane in place serves as a natural support for the finger or thumb of the party doing the glazing, thereby facilitating this work and reducing the cost.

To provide for inserting the glass panes without the necessity of detaching the glazing clips from the sash bars and to also provide for frictionally holding the glazing clips in operative position and against the glass panes, the body portion 9 of each glazing clip is made to normally bow with its convex face on the side of the transverse flange portion 10. Furthermore, the amount of bow and location of the pivot for the glazing clip are such that when the glazing clip is in inoperative position or swung from a position engaging the glass pane through an angle of approximately ninety degrees, the free end of the body portion and the transverse flange portion extend over the bar flange to which the glazing clip is secured, as shown particularly in Figure 4, at which time the outer edge of the transverse flange portion is substantially flush with the face of the bar flange to which the clip is secured. It will thus be seen that with the glazing clip swung to inoperative position the glass pane may be readily inserted into the sash. Furthermore, with this arrangement it will be seen that when the glazing clip is swung to operative position as by pressing upon its transverse flange portion its body portion will be compelled to straighten and it will frictionally grip the adjacent face of the bar flange to thereby hold the glazing clip in operative position.

With this construction of glazing clip it is possible to pivotally connect a pair of glazing clips for different glass panes by means of a single securing means 11, such as

a bolt and nut or a rivet. Also it is possible to secure the glazing clips to the sash bars in the factory and before shipment to thereby avoid possibility of their loss and make for 5 cheaper assembly.

While I have shown and described a specific form of glazing clip embodying my invention, I am aware that other specific forms within the scope of the appended claims may 10 be used.

What I claim as my invention is:

1. In a window, the combination with a sash bar and a glass, of means for securing said glass to said bar, including a resilient 15 clip having a portion frictionally bearing upon said bar and another portion for engaging said glass.

2. In a window, the combination with a sash bar and a glass, of means for securing 20 said glass to said bar, including a clip for engaging said glass, said clip having a resilient normally bowed portion frictionally bearing upon and gripping said bar in the operative position of the clip.

3. In a window, the combination with a sash bar and a glass, of means for securing 25 said glass to said bar, including a clip having a resilient normally bowed portion for frictionally bearing upon and gripping said bar and a transversely extending portion for engaging said glass.

4. In a window, the combination with a sash having a sash bar and a glass, of means 35 for securing said glass to said sash, including a clip pivotally connected to said bar and having a resilient normally bowed portion and a transverse portion near the free end of the normally bowed portion arranged to respectively frictionally grip said bar and

40 engage said glass in the operative position of the clip and to extend over said bar in the

inoperative position of said clip to provide for inserting the glass into said sash.

5. In a window, the combination with a sash having a sash bar and glass panes upon 45 opposite sides of said bar, of means for securing said glass panes to said sash, including clips upon opposite sides of said bar, a common pivot extending through said sash bar and clips for pivotally connecting the 50 latter to said bar, each of said clips having body portions extending longitudinally of said bar in opposite directions from the pivot aforesaid terminating at the outer ends thereof in transverse portions engageable 55 with the glass panes to hold the same upon the said bar.

6. In a window, the combination with a sash having a sash bar and glass panes upon 60 opposite sides of said bar, of clips for securing said glass panes to said sash, said clips being arranged upon opposite sides of said bar in frictional engagement therewith and having the inner ends thereof pivotally secured to said bar by means of a common pivot and having the outer ends thereof extending in opposite directions from the said pivot and engageable with the glass panes.

7. In a window, the combination with a sash bar and a glass, of means for securing 65 said glass to said bar including a clip having a portion normally frictionally engaging the said bar and connected thereto, and a laterally offset portion curved in a direction substantially parallel to said bar for engaging said glass and compensating for variations in the thickness of said glass or the thickness of the putty for the said glass or the combination of both.

In testimony whereof I affix my signature.

GUSTAF IVAR BARCLAY.
